UNITED STATES PATENT OFFICE.

THEODORE G. KOHL, OF WAUSAU, WISCONSIN.

CHIMNEY CLEANER.

Application filed March 24, 1921. Serial No. 455,045.

To all whom it may concern:

Be it known that I, THEODORE G. KOHL, a citizen of the United States, residing at Wausau, in the county of Marathon and State of Wisconsin, have invented certain new and useful Improvements in Chimney Cleaners, of which the following is a specification.

This invention relates to chimney cleaners and particularly to a chimney cleaner which is adapted to remain in the chimney at all times. An object of the invention is to provide a chimney cleaner which leaves a clear passage for the falling soot which it dislodges from the chimney, and a further object is to provide a chimney cleaner which presents no obstruction to falling soot when it is in inoperative position. A further object is to provide a chimney cleaner in which the cleaning element acts upon approximately one-half of the chimney periphery at a time, thereby leaving substantially one-half of the chimney clear for falling soot. More particularly a further object is to provide an apparatus of the character described in which the cleaning element is effectively maintained in contact with the portion of the chimney wall upon which it is operating.

The advantageous features above specified are attained in the specific embodiment of my invention which is illustrated in the accompanying drawings, in which—

Fig. 1 is an elevation, partly in section, of a chimney equipped with the invention,

Fig. 2, is a vertical section taken at right angles to Fig. 1;

Fig. 3, is an enlarged vertical section of the lower portion of the apparatus.

Fig. 4 is a horizontal section through the chimney and showing the cleaning element in operative position.

Fig. 5 is a perspective view showing the manner of attaching the cleaning element to the chain.

Fig. 6 is a perspective view of a portion of the cleaning element.

Fig. 7 is a perspective view of the stop mechanism.

In the drawings 1 indicates a chimney equipped with the invention, and provided with the customary lining 1', the usual inlets for pipes, only one pipe 2, however being shown, and with the usual soot collecting pan 3.

Between the lowest pipe 2 and the soot

pan 3, the chimney is provided with an opening in which is located a supporting frame 4, which is held in place by bolts 5, 5 which pass through external flanges 6, 6 on the frame and angle bars 7, 7 located within the chimney. A shaft 8 passes through and is loosely journaled in frame 4 and is provided with an inner yielding bearing 9, which comprises a spring wire 65 coiled about the shaft 8 and carried by the lower angle bar 7 by means of fastenings 10, 10. The shaft 8 is positioned in the frame 4 by means of an internal collar 11 and an external gear 12, both of which are 70 provided with set screws for clamping them to the shaft. Due to the yielding bearing 9, the shaft 8 has some angular movement through the frame 4 but a good bearing is maintained at frame 4 by the conical face 75 11' of the collar 11. Gear 12 is driven by a toothed hand wheel 13 mounted on a plate 14, which is provided at one end with an opening through which shaft 8 passes. The other end of plate 14 is attached to the 80 chimney by means of a lag screw 15. As illustrated, the plate 14 is arranged in vertical position so that hand wheel 13 lies below the shaft 8, but it is obvious that hand wheel 13 may be swung upwardly by properly positioning the plate 14, and such an arrangement may be desirable when the lowest position of wheel 13 would interfere with the soot pan 13. For convenience in installation or repair the frame 4 is preferably 85 provided with a door 16.

The inner end of shaft 8 carries a sprocket or other driving wheel 17, and a flanged pulley 18 is supported above sprocket 17 and near the upper end of the chimney by means 95 of a threaded rod 19. The rod 19 passes through the threaded plate 20 on the interior of the chimney and is held in position by means of a nut 21, which engages a plate 22 through which the rod 19 passes freely. 100 An endless band or chain 23 passes over sprocket 17 and pulley 18 and carries a member 24 to which the cleaning element is attached. The preferred form of member 24 is illustrated in Fig. 5 and said member 105 comprises a channel member carrying pivots 25 and 26 which are spaced apart by a distance equivalent to the length of one link of the chain 23. One pivot 25 passes through the end of one link of the chain and the other 110 pivot 26 carries a hook 27 for engaging the link at the opposite end of chain 23. The

ends of channel member 24 are extended beyond the pivots 25, 26 to form supports for plates 28, 29 between which the cleaning element is clamped. As shown in Fig. 5 plates 28, 28 are notched at the inner side to provide a central projection 29 and side projections 30, 30'. The central projection 29 is bent at right angles to the body of the plate and is attached to channel members 24 by means of rivet 31. The plates are identical in construction but are connected to member 24 with the projections 29 extending in opposite directions, thereby giving increased rigidity to the construction. The cleaner proper which is clamped between the plates 28, 28 comprises a brush or scraper which in plan, is substantially equal in area to one-half the cross-section area of the chimney flue. The brush or scraper may be formed of wire or other suitable material, but I prefer to form the cleaner from two metal plates 32 by slotting or cutting away portions of the plates to leave arcuate scrapers 33. The spacing of the scrapers 33 is such that when two plates 32 are superposed with the arcuate scrapers curving in opposite directions, as shown in Fig. 4, the working ends of one set of scrapers 33 will overlie the gaps between the working ends of the other set of scrapers 33. The scrapers 33 are given such a curvature that the working end of any given scraper is not located on a line normal to the chimney wall and passing through the supporting end 34 of the scraper. The width of the scrapers narrows down from the free ends towards the supported ends thereof, and this construction may be attained either by cutting the opposite sides along lines of different rates of curvature or by cutting along lines of the same rate of curvature but with the centers of curvature offset. The plates 32 are made of thin metal and are slightly larger than the chimney in which they are to be employed. As the scrapers 33 are resilient they will yield in their own plane to allow the introduction of the cleaner into the chimney and in use the individual scrapers will yield, as shown at X in Fig. 4, in passing over depressions or projections on the face of the chimney. Also, and due to the arcuate form of the scrapers, the cleaning end 33' of the scrapers may readily swing out of the plane of the plate in passing large projections, as shown at y, Fig. 4. This swinging or tilting of the end 33' of a scraper 33 not only allows it to clear the projections in the chimney, but aids in discharging any soot which may have lodged on the scraper. A further point to be noted in connection with the arcuate form of scraper is that except for incidental tilting of the individual scrapers as they pass over large projections, the scrapers 33 lie substantially in the plane of the plate 32. This is of importance as the scrapers are thereby

presented normal to the surface upon which they operate and there is no tendency for the scrapers to dig into the wall or to bind in the chimney as would be the case if the resilient scrapers were flared out of the plane of the plate 32.

To hold the cleaning element in contact with the surface of the chimney, I provide a spring 35, which may be substantially circular in shape, and the opposite ends of the spring are connected to the plates 28 by any suitable means. For securing greater resiliency, the spring 35 is preferably provided with coils 36, 36. The spring 35 may be arranged to contact with a corner of the chimney, as shown in full lines in Fig. 4, though if desired, the spring may contact with the opposite wall, substantially as shown at 35'.

A movable stop is provided for positioning the cleaner vertically in the chimney shaft when the apparatus is not in use. The stop comprises a crank 37 pivoted in a bearing plate 38 which is carried on the lower angle bar 7 and the outer end of the stop carries an arm 39. When the cleaner is moved against the crank 37 as indicated by the arrow in Fig. 3, the crank 37 rotates in bearing 38 until the arm 39 engages the angle bar 7. If the cleaner approaches the stop from the opposite side a similar movement may take place. The cleaner is thereby positioned in a vertical position and the flue is substantially free from obstruction regardless of the direction from which the cleaner approaches the movable stop. When the cleaner is installed in a chimney the length of the chain 23 is so adjusted that a stress will be set up in the spring bearing 9 which will tend to pull the shaft 8 downward. When the chain 23 becomes heated by the products of combustion which pass through the chimney, any expansion will be taken up by the tension in the chain due to the stress originally set up in the spring bearing.

When it is desired to clean the chimney in which the apparatus is installed the hand wheel 13 is rotated and the brush is carried up one side of the chimney, thereby scraping the accumulated soot from the walls. As substantially one-half of the flue is unobstructed, the soot may readily fall down into soot pan 3. Continued rotation of the hand wheel 13 carries the cleaner over the pulley 18 and down the other side of the chimney, thereby cleaning the other half of the walls. Due to the spring 35 and to the resiliency of the scrapers 33, the scrapers maintain an effective contact with the walls of the chimney, even though the interior of the chimney may not be exactly vertical or may have a rough surface. The yielding bearing 9 permits the shaft 8 to move to a limited extent, thereby cooperating with spring 35 in allowing the cleaner to adjust 180

itself to inequalities in the surface of the chimney.

While the specific embodiment above described is the preferred form of my invention it is to be understood that the invention is not limited thereto, but that changes may be made in the various elements and in the relative size, shape and location of the same.

10 I claim:—

1. A chimney cleaner comprising an endless band within the chimney, means for supporting and driving said endless band, a cleaner mounted on said endless band and 15 consisting of a plurality of superposed sets of arcuate scrapers arranged substantially in planes normal to the chimney walls.

2. A chimney cleaner as claimed in claim 1 in which the adjacent sets of arcuate 20 scrapers are curved in opposite directions.

3. A chimney cleaner comprising a pulley located within a chimney and near the upper end thereof, a band supported on said pulley, means for moving said band, a 25 cleaner carried by said band and movable over said pulley, said cleaner having a working face contacting in operation with substantially one-half the inner periphery of the chimney, and a spring for holding said 30 cleaner in contact with the walls of the chimney.

4. A chimney cleaner as claimed in claim 3 in which said cleaner comprises a plurality of sets of arcuate scrapers arranged 35 substantially in planes normal to the chimney walls, the adjacent sets of arcuate scrapers being curved in opposite directions.

5. A chimney cleaner comprising an endless band within a chimney, a cleaner carried 40 by said band and having a working face contacting in operation with substantially one-half the inner periphery of the chimney, and a movable stop for arresting said cleaner in a vertical plane as said cleaner moves into 45 inoperative position.

6. A chimney cleaner comprising an endless band within a chimney, a cleaning element carried by said band, upper and lower rotatable elements for supporting said band, means for driving said band and means for 50 tensioning said band.

7. A chimney cleaner comprising an endless band located within a chimney, a cleaning element carried by said band, upper and lower rotatable elements for supporting said 55 band, means for rotating one of said elements for driving said band, and means biased to urge said elements apart for tensioning said band.

8. A chimney cleaner comprising a shaft 60 extending into a chimney near one end thereof, a sprocket on said shaft, a pulley within and near the other end of the chimney, an endless band supported by said sprocket and pulley, a cleaning element mounted on said 65 endless band, and means including a yielding bearing for supporting said shaft.

9. A chimney cleaner comprising a shaft extending into a chimney near one end thereof, a sprocket on said shaft, a pulley 70 within and near the other end of the chimney, an endless band supported by said sprocket and pulley, a cleaning element mounted on said endless band, and means 75 for supporting said shaft and tensioning said band.

10. A chimney cleaner comprising a supporting frame attached to a chimney near the lower end thereof, a shaft having one end journaled in said frame and extending 80 into the chimney, a yielding bearing mounted on said frame and supporting the opposite end of said shaft, a sprocket on said shaft, a pulley located within and near the upper end of the chimney, an endless band 85 passing around said sprocket and pulley and a cleaning element carried by said band.

In testimony whereof, I affix my signature.

THEODORE G. KOHL.
